WASHING MACHINE

Austin E. Koon, Gainesville, Tex.

Application January 8, 1935, Serial No. 854

1 Claim. (Cl. 68—18)

This invention relates to washing machines and it has particular reference to such a machine designed primarily for domestic use.

- The principal object of the invention is to improve upon laundering machines and apparatus from the standpoint of simplicity of construction and economy and especially on those machines designed for use in rural sections where little provision is made for electrical power.
- Another object of the invention is to provide a machine which not only washes clothing but likewise effectively rinses, extracts and dries the same. Accordingly, the machine is extremely useful for laundering clothes in inclement weather when it is impossible or undesirable to hang the garments out of doors for the purpose of drying the same.

With the foregoing objects as paramount, the invention has particular reference to its salient features of construction and arrangement of parts which will become manifest as the description proceeds, taken in connection with the accompanying drawings, wherein:—

Figure 1 is a perspective view of a machine constructed according to the present invention with portions broken away to show the interior thereof.

Figure 2 is a longitudinal section.

Figure 3 is a fragmentary detail view of the mounting for the wheel provided for rotating the cylinder.

Figure 4 is a transverse section of the machine with the hood removed and showing the hinged portion of the cylinder displaced preparatory to receiving garments.

Figure 5 is a diametrical section of the cylinder, and

Figure 6 is a detail view in perspective showing the divider for separating the cylinder into a plurality of compartments.

Continuing with a more detailed description of the drawings, reference is primarily made to Figure 1 in which is shown a preferably rectangular receptacle 1 having a liquid outlet 2 and to which is connected a hose 3 which may be of any desired length so that the receptacle 1 may be drained and refilled without removing the same from a stove or other heating medium, if desired.

The receptacle 1 is provided with handles 4 at either end for convenience in handling. A reinforcing strip 5 embraces the top of the receptacle and as apparent in Figure 4, U-shaped recesses *a* are provided on either side of the receptacle midway between its ends to receive

the ends of stub shafts 6 affixed to either side of a cylinder 7.

The stub shafts 6 are affixed to or integral with spider mounts 8, the latter being secured to the walls or ends of the cylinder 7 by means of rivets 9. The cylinder or drum 7 is constructed preferably by bending a sheet of material at equidistantly spaced intervals to provide fins or vanes 10 in the manner shown particularly in Figures 2 and 5. When the strip of metal is shaped into a cylinder, the fins 10 are directed radially inwardly. The walls or ends of the cylinder are affixed by means of soldering, welding or crimping as may be found the most desirable or economical but it is preferred that the diameter of the ends be slightly greater than that of the cylinder to provide protruding edges *b* which will afford a protection for the cylinder when the latter is removed from the receptacle 1 and placed on the floor.

The cylinder 7 is divided into two sections, one of which is approximately two thirds larger than the other to provide a means for opening the cylinder for the reception of the garments to be laundered. The smaller section is hinged at *c* to the larger section so that the smaller section may be displaced in the manner shown in Figure 4 as the hood 11 is removed from the receptacle 1. The cylinder 7 is provided with a multiplicity of perforations 12 around its entire circumference for the purpose to be hereinafter explained.

In the operation of washing clothing, the receptacle 1 is first partially filled with water and a desired amount of soap or washing powders placed in the water. The receptacle 1 is then set down upon a stove or other heating means and the water is heated within the receptacle. The cylinder 7 is then filled with clothes. The cover or hinged section of the cylinder is closed and secured by passing the hooks 13 under the pin 14, carried by the larger section of the cylinder. The cylinder is then placed in the receptacle 1 so that the stub shaft 6 will rest in the U-shaped recesses *a* of the receptacle. The hood 11 is then placed upon the receptacle 1 as shown in Figure 1. A crank (not shown) is then inserted into the squared aperture 23 shown in Figure 1 and the cylinder is slowly rotated or oscillated to and fro in the receptacle 1. This action obviously thoroughly saturates the clothing since the saponified solution passes through the apertures 12 in the cylinder and this solution, together with the beating action to which the garments are subjected by coming into contact with the fins 10 loosens the dirt which passes out

through the apertures 12 into the receptacle 1. When the garments have been cleaned, the liquid is drawn off through the hose 3 into a suitable receptacle and clean water substituted. The cylinder 7 is again rotated until the clothes are thoroughly rinsed. The rinsing water is drained off and if desired, bluing is added to a new supply of water, the cylinder is again rotated and the bluing water is drained off. The cylinder 7 is then opened and the clothing removed. Extraction of the water retained in the garments is now required.

Extraction of water in the garments is accomplished by first opening the cylinder and removing the clothing and the divider shown in Figure 6 is installed in the cylinder. This divider is constructed by bending a sheet of metal 17 to the form shown in Figure 6 and ribs 18 are produced therein by crimping the sheet transversely. Another piece of material 19 is similarly crimped at 18 and affixed to the point where the sheet 17 is bent, thereby forming a divider, dividing the cylinder 7 into three compartments as shown in Figure 5. The outer ends of the partitions thus formed are bent in U-shape at d so as to receive certain of the radially disposed fins 10 in the cylinder 7. This is likewise illustrated in Figure 5. Thus it will be seen that since the weight of the clothing is equally divided in the cylinder 7, it is less difficult to rotate and when rotated, water is drawn out of the garments centrifugally through the apertures 12. This action removes the surplus water from the garments and when sufficiently dry, the extracted water is drained from the receptacle 1.

When the extracting and drying process is carried out, it is necessary that the cylinder 7 be rotated at a higher rate of speed than is necessary during the washing process. For this purpose, the invention provides an attachment such as shown in Figure 1, in the form of a pulley or wheel 20 which is mounted upon a stub shaft 21 extending outwardly from the receptacle 1. A smaller pulley 22, having a squared aperture 23 is provided to receive the squared end 16 of the stub shaft 6. A V-type belt 24 surrounds the pulleys 20 and 22 and the entire assembly is encased in the housing 25 so that it may be mounted in the manner shown in Figure 1 as a unit and very readily removed. The crank 15 is then applied to the shaft 26 of the pulley 20 and

due to the increased ratio of pulley 20 over that of pulley 22, the cylinder 7 may be rotated at a very high rate of speed. In the extracting process, this is highly desirable since the water is drawn from the clothing through the apertures 12 in the cylinder 7 into the receptacle 1 from which it is drained off through the hose 3.

In drying, the receptacle 1 is placed or allowed to remain on the stove or other heating medium and perhaps elevated so that the flames will not come into direct contact with the bottom of the receptacle and the cylinder 7, through the medium of the pulley and belt combination shown in Figure 1 is rotated at a high rate of speed and the dry air within the receptacle is effective in drying out the garments, especially since the excess water has already been extracted. It will be understood that the fins 10 in the cylinder and the protuberances provided in the divider are effective in tumbling the clothing within the cylinder, thereby exposing the maximum surface to the dry air.

Manifestly, the construction shown is capable of considerable modification and such modification as is considered within the scope and meaning of the appended claim is also considered within the spirit and intent of the invention.

What is claimed is:

The combination in a washing, extracting and drying machine, a receptacle having a liquid inlet and a hood, a perforated, cylindrical material retaining housing disposed in said receptacle and having bearing spindles rotatably mounted in the ends of said receptacle, said housing being provided with a hinged section to admit material for processing, a series of inwardly directed transverse ribs in said cylindrical housing, a flanged member arranged to be detachably mounted in said cylinder and having radial walls to divide the same into a predetermined number of sector shaped compartments and whose radial members are formed at their ends to be detachably connected to certain of the ribs of said cylindrical housing, a pulley carried by one of the spindles of said housing, a second and larger pulley spaced from said first pulley, a belt surrounding said pulleys and means to rotate either pulley.
